UNITED STATES PATENT OFFICE

RAYMOND GRIESER, OF DETROIT, MICHIGAN, ASSIGNOR OF ONE-HALF TO LLOYD C. FELTS, OF DETROIT, MICHIGAN

DESIGN FOR A CURTAIN TIE-BACK OR SIMILAR ARTICLE

Application filed November 24, 1931. Serial No. 41,848. Term of patent 7 years.

To all whom it may concern:

Be it known that I, RAYMOND GRIESER, a citizen of the United States, residing at Detroit, in the county of Wayne, and State of Michigan, have invented a new, original, and ornamental Design for a Curtain Tie Back or Similar Article, of which the following is a specification, reference being had to the accompanying drawing, forming part thereof.

I claim:

The ornamental design for a curtain tie back or similar article, as shown.

RAYMOND GRIESER.
